HEATER

Benjamin Kirsch and Albert Benjamin Medville,
Chicago, Ill., assignors to Auto Radiator Mfg.
Co., Chicago, Ill., a corporation of Illinois

Application December 28, 1935, Serial No. 56,421

2 Claims. (Cl. 257—137)

This invention relates to heaters and with regard to certain more specific features to automotive heaters.

Among the several objects of the invention may be noted the provision of a heater having an improved conformation, whereby a better shape is obtained for use in motor cars; the provision of a heater of the class described which has an improved, plural-branch air circulating feature, whereby selectively controlled circulation may be effected; and the provision of a better arrangement between the core, shell and air circulating parts. Other objects will be in part obvious and in part pointed out hereinafter.

15 The invention accordingly comprises the elements and combinations of elements, features of construction, and arrangements of parts which will be exemplified in the structures hereinafter described, and the scope of the application of which will be indicated in the following claims.

In the accompanying drawings in which are illustrated several of various possible embodiments of the invention,

Fig. 1 is a plan view of the heater showing certain deflectors adjusted forwardly;

Fig. 2 is a front elevation of Fig. 1;

Fig. 3 is a left-side elevation of Fig. 2;

Fig. 4 is a vertical section looking forward and taken on line 4—4 of Fig. 3;

30 Fig. 5 is a horizontal section taken on line 5—5 of Fig. 2;

Fig. 6 is a fragmentary sectional detail of a frictional holder for a deflector;

Fig. 7 is a perspective detail of a deflector support;

Fig. 8 is a fragmentary view showing a modified drive; and,

Fig. 9 is a rear elevation.

Similar reference characters indicate corresponding parts throughout the several views of the drawings.

Heretofore, many automotive heaters have been made of a shape wherein the core has had a vertical dimension not less than the horizontal dimension thereof, and usually, this vertical dimension has been longer than the horizontal dimension. In the few instances where the horizontal dimension has been made longer than the vertical dimension, the old feature of a single flowing column of air through the apparatus has been used for distributing heat from the core to the surroundings.

This invention makes use of the horizontal dimension which is greater than the vertical and 55 which provides a more efficient Y-shaped flow

of air through such a conformation. Thus there is obtained a conformation of heater which fits better into the limited head room available in a motor car, the lateral increase in dimension being of no disadvantage because lateral room is available; and this is done without sacrifice of efficiency in conveying the heat in the heater to the surrounding atmosphere.

Referring now more particularly to Figs. 1 to 5, there is shown at numeral 1 an outer decorated shield having its forward face formed into retaining cylinders 3, having exit openings 5 therein. The total width between the lateral edges of cylinders 3 is greater than that of the remainder of the enclosure of the heater.

10 Within the openings 5 are rotatively carried rotary deflector supports or rings 7 having flanged portions 9 bearing against the inner peripheries of the openings 5 as shown in Fig. 5. The flanges 9 are provided with gear teeth 11 which mesh with teeth on a common pinion 13 which is attached to and under control of a control knob 15. The pinion 13 is clamped between the inner end of the control knob 15 and a spring 17 which is held to said knob by a screw 19. The knob 15 15 being rotary in the shield 1, is thus adapted upon turning, to drive the ring supports 7 simultaneously in the same direction, clockwise or counterclockwise.

15 The relative angular positions of the two rings 7 may be changed by loosening the screw 19 and backing the pinion 13 out of mesh with the rings 7, and then relatively rotating whichever ring it is desired to adjust, and again meshing with the pinion and tightening the screw.

20 The ring supports 7 are resiliently held in the openings 5 by means of spring members 21 illustrated in Fig. 7 which press the rings 7 outwardly so that the flanges 9 engage against the insides of the openings 5.

25 Each ring support 7 carries oppositely disposed frictional clamp members 23, detailed in Fig. 6. Each clamp member 23 comprises a slot 25 which springingly engages inner gudgeons 27 of parallel reaches of relatively rigid rods 29. These rods 29 30 have gudgeons 31 at their opposite ends frictionally held in a clamp 26, which is similar to clamp 23. Both clamps 23 and 26 carry pins 33 for preventing inadvertent removal of the gudgeons 27 and 31, respectively.

35 Each outer clamp 26 carries a deflector wing 35. A plurality of the deflector wings described are used, two in each ring 7. As shown in Figs. 1 and 5, the wings 35 may be selectively drawn outwardly to selectively open the passages through 55

the rings, and they may be adjusted parallel to the rings or at suitable angles. The frictional engagements between the gudgeons 27 and 31 and their respective clamps 23 and 26 maintain a given adjustment. This adjustment is independent of the adjustment at knob 15.

In Fig. 8 is shown an alternative drive for the rings 7 consisting of a pinion 37 driven from said knob 15, which, while it is meshed with one of the gears of one of the rings 7, has clearance at its addendum with the addendum of the teeth of the other ring 7. However, the pinion 37 is meshed with an idler 39 which in turn meshes with the ring 7 not meshed with by the pinion 37. By this alternative construction, it is possible with a single rotation of the knob 15 to cause the rings 7 to rotate in opposite directions. From the above, it will be seen that with a single turn of the knob 15, the rings may be simultaneously rotated either with the deflectors 35 outwardly adjusted or closed.

The radiator core per se is shown at numeral 41. From Fig. 4 it will be seen that the shield 1 has a generally rectangular shape, with the cylinders 3 bulging therefrom. The rectangular shape accommodates the generally rectangular shape of the core but this leaves arcuate portions within the cylinders 3 which are difficult to fill in with core material and which if not filled, permit passage of cold air. Therefore, the core is provided with arcuate, air-blocking fillers 43, as shown in Fig. 9 which fit into the arcuate portions of the cylinders.

Behind the enclosure shield 1 is an enclosing member 45 which is fastened to the shield by screws 47 (see Figs. 1 and 2). The enclosing member has bolted thereto a supporting bracket 48. This bracket has rigidly fastened thereto threaded bushings 49 for loosely accommodating respectively an inlet pipe 51 and an outlet pipe 53, the pipes 51 and 53 passing to the usual upper and lower tanks 52 and 54 respectively of the core 41. The pipe 51 attaches to the upper tank 52 at the upper left-hand region of the heater (viewed from the rear), and the pipe 53 attaches to the lower right-hand region of a lower tank 54. Thus circulation of hot water from the top to the bottom of the heater is obtained, and at the same time, a cross-flow is obtained in the upper and lower tanks.

The bracket 48 also has fastened thereto a motor 55 for driving an air circulating fan 57 which is located between the pipes 51 and 53. The fan draws air through an opening 56 in the enclosing member 45 and projects the air through the core 41 and out through the two openings 5

in the rings 7 provided the wings 35 are adjusted to open position. From the above it will be seen that the fan draws a single stream of air into the opening in the enclosure 45 which branches out into two streams emanating from the rings 7, each stream being individually controllable as to lateral and vertical distribution. If desired, one stream may be cut off entirely, or both.

It will be seen from Fig. 9 that not only do the inlet and outlet pipes 51 and 53 have a relative diagonal relationship with respect to the heater, but the mounting bushings 49 do also. This provides by means of a single pair of mountings a great resistance against vertical and lateral movements of the heater under jarring action from the automobile.

It will be seen that the shield 1 and the member 45 form an encasement enclosure for the core 41 which also functions as a support. The forward face of the core is aligned by suitable stops 60 (Fig. 4). This enclosure has a single-opening inlet and a plurality of outlet openings constituted by the rings 7.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

We claim:

1. An automotive heater comprising a core, an enclosing means around the core, a means associated with the core and forming an air passage therethrough, said enclosing means having a plurality of outlet openings for said air, an adjustable air deflector associated with each opening, and a single means for simultaneously adjusting both deflector means in opposite angular directions.

2. An automotive heater comprising a heating core, an enclosure surrounding said core and having an air inlet behind the core, and a plurality of air outlets in front of the core, angularly manually adjustable means located in the respective outlets, a single manual control means for the angular adjustable means, means articulating said control means and the adjustable means whereby the latter are simultaneously manually adjustable, and independently, manually adjustable deflector means in the respective outlets.

BENJAMIN KIRSCH.

ALBERT BENJAMIN MEDVILLE.
